COATING APPARATUS

Wiltie I. Gladfelter and William H. Moore, Philadelphia, Pa., assignors to Crown Cork & Seal Company, Inc., Baltimore, Md., a corporation of New York

Application November 14, 1940, Serial No. 365,698

14 Claims. (Cl. 91—45)

This invention relates to machines for coating articles of manufacture, such as containers or cans. More particularly, the invention relates to a machine for coating certain portions of such articles during their manufacture.

Although not confined to such use, the machine of the present invention is adapted to coat, with a resistant coating material such as lacquer or enamel, the outer surfaces of the outwardly projecting seaming flanges at the bottom ends of drawn seamless can bodies of the type, for instance, as are shown in the application of Calleson et al., Serial No. 334,876, filed May 13, 1940, which can bodies may be made in accordance with the application of Calleson et al., Serial No. 280,650, filed June 22, 1939. After such can bodies are drawn and formed, their bottom ends may be trimmed and flanged in accordance with the application of Gladfelter et al., Serial No. 341,754, filed June 21, 1940. The flanged bodies are then coated interiorly, for instance, by the use of a machine similar to that shown in the application of Goebel et al., Serial No. 154,108, filed July 16, 1937, or by a machine of the type shown in the application of Gladfelter et al., Serial No. 367,454, filed November 27, 1940.

Before the containers are transferred from such an inside coating machine to a first baking oven, as described in the application of Gladfelter et al., Serial No. 347,564, filed July 25, 1940, it has been found desirable to coat the exterior surfaces of the seaming flanges and the adjacent portion of the side walls, to the end that this coating may be baked simultaneously with the aforesaid inside coating. After the baking operation, the containers are passed through a double-seamer, where bottom end members are secured upon the coated flanges, as described in the last-mentioned application. It is important that both surfaces of the seaming flanges be coated before the flanges are curled up into a double-seam with the flanges of the end closure members.

The principal object of the present invention is to provide a machine that will take a line of such containers from an inside coating machine and apply to the exterior surfaces of the seaming flanges, an even, continuous coating of lacquer or enamel, and then deliver the coated containers to a conveyor leading to a baking oven.

A further object of the invention is to provide an extremely simple machine of high capacity, that will handle a rapidly moving line of such

containers and perform its coating functions in a reliable and expeditious manner.

A further object of the invention is to provide means for taking the containers in horizontal

position directly from an inside coating machine; to provide means for presenting the containers to a coating device, such as a spray gun, in such manner that only the desired portions of the containers are coated; to provide means for rotating the containers while being coated, so that the coating is applied evenly, and to provide means for delivering the containers in such manner as to avoid smearing or marring the coated surfaces.

It is a further object of the invention to provide novel means, in a machine of this class, for handling the containers, for rotating them during the coating operation, and for depositing the containers in upright position upon a discharge conveyor.

A further object of the invention is to provide novel means for guiding the containers during their passage through the machine, for projecting portions of the containers into the spray area, and for holding them in the desired position during the rotation of the containers about their axes.

Other and further objects and advantages of the invention will be apparent to those skilled in the art from a consideration of the following description of an illustrative embodiment of the invention, shown in the accompanying drawings.

In the drawings:

Figure 1 is a rear elevation of the machine.

Figure 2 is a partial end elevation, with certain parts in section, looking from the right of Figure 1.

Figure 3 is a front elevation taken from the right of Figure 2.

Figure 4 is a central vertical section through Figure 3, on an enlarged scale.

Figure 5 is a substantially vertical, transverse section of the conveyor chain and associated parts in the position they assume as they approach the coating chamber.

Figure 6 is an end elevation taken from the left of Figure 5.

Figure 7 is a fragmentary end elevation taken from the right of Figure 5, and

Figure 8 is a view similar to Figure 5, showing the relation of the parts at the container discharge position.

As shown in Figure 1, a conveyor chain 10 is trained for movement in a vertical plane about sprockets 11, 12, 13 and 14, the sprocket 11 be-

ing journaled in a support 15 which may be a part of, or may be positioned in fixed relation to, an inside coating machine of the type referred to above. Sprockets 12 and 13 are journaled on stub shafts carried at the upper ends of two pairs of posts 16, 17, mounted in pedestals on the floor. The idler sprocket 14 is similarly carried by a stub shaft carried by brackets clamped upon the posts 16. Preferably, the sprocket 11 is positively driven by and at the same speed as the outfeed dial of the inside coating machine. Hence, that sprocket acts as the driving means for the chain 10.

The chain moves upwardly on an inclined plane between the sprockets 11 and 12 and then passes horizontally through a coating chamber represented generally at 20, the chamber being supported by a base 21 projecting upwardly from the floor. During its movement toward the sprocket 13, the chain travels along in substantially parallel relation to the lower flight of a pair of conveyor cables 22 leading toward a baking oven or the like. Between the sprockets 11 and 12, the chain is supported upon a track 23 which may take the form of an angle iron supported at one end by the pedestal 15 and at the other end by a flange 24 carried by one of the posts 16. The support 21 for the housing 20 carries laterally projecting tracks 25, 26 over which the chain 10 slides, the latter track being extended toward the sprocket 13 and being appropriately secured to a flange 27 at the upper end of one of the posts 17.

As shown in Figures 4, 5 and 6 alternate links 10a of the chain 10 are provided with downwardly projecting, laterally bent wings 30 adapted to slide upon the tracks 23, 26, etc. The intermediate links 10b have upwardly projecting laterally bent wings 31, upon which transversely disposed plates 32 are bolted or otherwise secured. Each plate 32 terminates at one end in a bearing sleeve 33 for a pivot pin 34, and, at the other end, in an upwardly projecting stop lug 35. A can body holding bracket 36, provided with downwardly projecting hollow bosses 37 is pivoted upon each pin 34, for transverse swinging movement with respect to the plate 32 and the chain 10. At the end remote from the pivotal connection, each bracket is shaped to provide apertured ears 38, carrying a pin 39 upon which a roller 40 is journaled. The brackets also include two pairs of upwardly and outwardly projecting arms 41, 42, shaped to embrace and receive the side walls of container bodies 45. The bracket arms 42 are extended rearwardly to provide an arcuate flange 43, connected to integral webs 44. The flange 43 has an upturned lip 46 at its rear edge and provides an arcuate groove for the reception of the edge of the outwardly turned seaming flange 45a of the container body 45.

Tension springs 47, connected at their opposite ends to pins 48, 49 carried respectively by the up-turned stop lug portion 35 of the plate 32 and the rear portion of the brackets 36, at all times urge the brackets 36 toward the horizontal position shown in Figures 2 and 5. Under the influence of guide rails having cam surfaces associated therewith, as hereinafter explained, however, the brackets 36 may swing from the normal, horizontal position to an inclined coating position and also to a substantially vertical discharge position adjacent the conveyor cables 22.

The base 21 for the coating chamber 20 is provided with a laterally projecting flange 50 which serves as a floor for the chamber and upon which a track plate 51 for the chain 10 is mounted. An overhanging guide strip 52, positioned above the rear portion of the track 51, overlies the wings 30 on the rear side of the chain, to prevent the chain being tipped laterally when the brackets and cans are swung laterally, as hereinafter explained.

The coating chamber 20 preferably is defined in part by an integral casting secured to the base 21. The casting includes a rear wall 55, and a top wall or ceiling 56 having a forwardly projecting web 59 extending upwardly therefrom and connected thereto by vertically disposed reinforcing flanges 57, 58, and a rearwardly projecting web 54. A motor and a spray gun may be carried by the web 59, as hereinafter explained. At the entrance and exit ends, the chamber is open above the floor 50, except for the spaces occupied by flanges 60, 61 which project downwardly from the top wall 56. The top wall or ceiling 56 projects forwardly beyond the line of the front edge of the floor 50, except for a central opening 62 defined by down-turned lateral flanges 63, 64. The forward edge of the top wall is similarly flanged as at 65, the flange lying in a plane disposed perpendicularly to the flanges 63, 64.

A sheet metal hood or casing 20' comprising a front wall 66 and end walls 67, 68 appropriately bolted together is carried by and closes the open front face of the chamber 20. At the upper, central portion, the hood 20' includes a removable, rearwardly projecting, top wall 69 terminating in an upwardly and rearwardly inclined section 70 closely fitting between the flanges 63, 64 and secured by wing nuts 71 or the like to the upper margin of the opening 62. The wall 69 is appropriately apertured for the reception of a downwardly facing spray gun 75 clamped upon a horizontally extending arm 76 carried by a bracket 77 adjustably clamped upon the lower end of a vertical post 78, supported, in turn, in a hollow boss 80, by a collar 81 disposed above the boss.

Since any conventional type of spray gun may be used, the specific construction of the gun 75 need not be described. Appropriate flexible conduits (not shown) for the atomizing air, the trigger air and the liquid coating material are adapted to be connected to nipples 75a, 75b, 75c, respectively, as is well understood in the art. Automatic or manual means may be provided to cut off the trigger air when the conveyor stops, if desired, to render the gun inoperative.

At its lower end the hood 20' is open and is connected to a downwardly extending flue 85, bolted to reinforcing angle irons 86 and to a flange 87 integral with the base 21 and reinforced by webs 88. The flue 85 may be of any appropriate construction and is preferably connected by a conduit to an exhaust fan, not shown.

The upper wall 56 of the chamber casing has laterally projecting extensions 90, 91 (Figs. 1, 2 and 3) which carry stub shafts 92, 93 upon which sheaves 94, 95 are journaled for rotation in a plane inclined substantially 45° from the vertical. The upwardly projecting flanges 57, 58 of the casting carry angularly disposed hollow bosses 96, 97, respectively, in which rods 98, 99 are held by set screws or the like. These rods are connected to a plate 100, upon which a base 101 for an electric motor 102 is bolted. The motor shaft

carries a driving sheave 103 for a V-belt 104 trained about that sheave and about the sheaves 94, 95, with its lower flight 105 guided through openings in the end walls 61, 68 of the hood 20'. As shown in Figures 1-4, the belt 104 is thus trained for movement on an inclined plane, with its lower flight disposed in the coating chamber adjacent the spray gun 75.

Interiorly of the chamber (Fig. 4) there is mounted a guide or cam rail 110, upon which the rollers 49 of the can supporting brackets ride. The rail has downwardly turned ends 111 secured in hollow bosses 112 associated with the flange 50 of the base 21. Inside of the chamber, the rail has an upwardly and forwardly inclined portion 113 which serves to swing the brackets 36 and the can bodies 45 from the normal, horizontal position to the inclined position shown in Figure 4, where the upper portions of the seaming flanges 45a are disposed on a line below the spray gun 75. When in this position and while passing beneath the spray gun, the side walls of the containers are urged into contact with the lower face of the lower flight 105 of the V-belt 104, with the result that, as the belt is driven, the can bodies are rotated in the supporting pockets of the brackets 36. As the containers approach the discharge end of the chamber, the rollers 49 encounter a downwardly and rearwardly inclined track section 113a, so that the brackets are again brought to a horizontal position, to enable the containers to clear the end flange 61 of the chamber 20 and the end wall 68 of the hood 20'.

Additional guide rails are provided in the chamber to retain the cans in the pockets of the supporting brackets and to prevent them from being inadvertently removed therefrom as a result of the rapid rotation imparted thereto by the belt 104. As indicated in Figure 4, a rail 115, having its ends secured in bosses 116, is shaped so as to follow closely the path of movement of the neck ends of the containers 45 as they travel through the chamber. A similar rail 117, secured to the casing at 118, is disposed opposite to and closely follows the movement of the side walls of the containers. A third rail 119, similarly secured to the ceiling of the casing, is disposed opposite to and closely follows the path of movement of the flanged ends of the containers.

After the coated containers, in horizontal position, leave the chamber 20, the rollers 49 again encounter a guide or cam rail 120 (Fig. 8) carried by the track section 26. This rail has an upwardly and forwardly inclined portion 121, adapted to swing the brackets 36 and the containers therein from the normal horizontal position to a vertical discharge position, above the conveyor cables 22. The containers are prevented from tipping off of the cables 22 as they are swung to vertical position and deposited thereon by a guide rail 122 extending parallel to the cables and secured to the track 26 by brackets 123.

Referring to Figure 1, it will be noted that the lower flight of the cables 22, although substantially parallel to the upper flight of the chain 10, is inclined upwardly somewhat in the direction of its movement. Hence, as the brackets 36 and the containers 45 travel with the cables 22, the cables raise the containers relative to the brackets and move the seaming flanges 45a upwardly relative to the lip 46 and thereby disengage the containers from the brackets, permitting the brackets to swing rearwardly and downwardly under the influence of the springs 47,

leaving the containers supported on the cables 22 in vertical position, the downward swinging movement of the brackets 36 being permitted by a suitable downwardly and rearwardly inclined portion of the track 121.

5 The cables 22 are trained about a sheave 125 journalled in bearings 126 carried by the upper end of a frame 127 mounted upon the floor adjacent the frame 21. A motor 128, operating 10 through a speed reducer 129, sprocket 130, chain 131 and a second sprocket 132 serves to drive the cables 22 at a predetermined speed relative to the chain 10.

In the operation of the machine of the present 15 invention, the interiorly coated can bodies are deposited, by the outfeed dial of the inside coating machine, not shown, into the brackets 36 carried by the chain 10, as the brackets move upwardly around the sprocket 11, the transfer being effected and the sprocket 11 being driven, preferably, in accordance with the disclosure of the application of Gladfelter et al., Serial No. 367,454, filed November 27, 1940. The horizontally disposed can bodies are accurately positioned with respect to the brackets, as they move 20 up the inclined track 23, by an appropriate guide rail 135 having its ends secured in brackets 136 secured to the track 23 (Fig. 5), so that the seaming flanges 45a substantially abut the arcuate lip 46 associated with the supporting flange 43. After the horizontally supported containers enter the coating chamber, they are swung upwardly from that position to the inclined position, by the rollers 49 encountering the inclined 25 portion 113 of the guide or cam rail 110. This movement serves to bring the side walls of the containers into contact with the lower flight 105 of the belt 104, the latter being driven in a direction opposite to the direction of movement of the containers. As indicated in Figures 1 and 3, the 30 can bodies are moved into contact with the belt, after they have passed under the sheave 95 and have moved into the chamber. While in this inclined position, and while being rotated by frictional contact with the belt 104 and held in the 35 pockets by the guide rails 117, 118, 119, the seaming flanges of the containers are projected above and beyond a longitudinally extending guard or partition plate 137. In this position the flanges 40 50 pass beneath the spray gun 75 and the outer surfaces of the flanges and the adjacent surfaces of the container side walls are evenly and smoothly coated.

After the containers move out of the spray area, 55 they again assume a horizontal position and pass out of the coating chamber in that position. The brackets and cans remain in the horizontal position as they move past the sheave 125, to permit the ends of the containers to clear that sheave, but as they approach the lower flight of the cables 22, the brackets and the containers are swung to the vertical position by the inclined portion 121 of the guide or cam rail 120, with the result that 60 the containers are deposited upon the cables 22 in upright position and are conveyed by those cables to a baking oven or the like.

65 It must be understood that the invention is not limited to the specific details of construction shown in the accompanying drawings and described above, but includes all modifications coming within the scope of the appended claims and their equivalents.

70 We claim:

75 1. An article coating machine comprising a coating chamber, a conveyor trained for move-

ment therethrough, article-holding brackets pivotally connected to the conveyor, means for continuously moving the conveyor and the brackets through the chamber, means for swinging the brackets and the articles relative to the conveyor, laterally from a horizontal position to an inclined position while passing through the chamber, a spray gun positioned to direct a spray of coating material upon the articles moving in said laterally swung inclined position, and means for swinging the brackets and the articles to a vertical position after the spraying operation, to discharge the articles from the brackets.

2. An article coating machine, comprising a coating chamber, a conveyor trained for movement therethrough, article-holding brackets pivotally connected to the conveyor for movement from a horizontal, article-receiving position to a vertical, discharge position, a spray gun in the chamber positioned adjacent the path of movement of the conveyor and adapted to spray the articles, means for swinging the brackets from said horizontal article-receiving position to an inclined position in the chamber as the articles pass the spray gun, and means beyond the spray gun for swinging the brackets to said vertical, discharge position after the completion of the spraying operation.

3. A machine for coating the exterior surfaces of outwardly projecting seaming flanges and the adjacent portions of the side walls of containers or the like, comprising a coating chamber, a vertically disposed, downwardly projecting spray gun in the chamber, means for receiving a line of containers in horizontal position and for moving the same through said chamber, means in said chamber for swinging the containers laterally to an inclined position to project their seaming flanges and the adjacent portions of their side walls laterally into a position below said spray gun as they move past the same, means for rotating the containers about their longitudinal axes as they pass the spray gun, whereby the seaming flanges and adjacent side wall portions receive an even coating from the spray gun, and means disposed exteriorly of the chamber for depositing the containers in upright position at a discharge station.

4. A machine for coating the exterior surfaces of outwardly projecting seaming flanges of containers, or the like, comprising a longitudinally elongated coating chamber, a spray gun associated therewith and positioned to project a spray of coating material in a localized zone spaced from the longitudinal center line of the chamber, a conveyor trained for movement longitudinally through the chamber, container-holding brackets pivotally carried by the conveyor and adapted to receive containers exteriorly of the chamber when in a receiving position, means for swinging the brackets and the containers laterally about an axis parallel to the conveyor from the receiving position to a coating position to project the seaming flanges into a position to pass through said localized zone as the brackets and the containers are moved past the spray gun, means for rotating the containers about their axes when in the latter position to expose all portions of their flanges to the spray, and means for swinging the brackets and the containers to a discharge position, after completion of the spraying operation.

5. An article spray coating machine comprising coating means, a conveyor trained for move-

ment past the same but out of range of the spray projected thereby, a plurality of brackets pivotally connected to the conveyor and having upwardly facing, concave article receiving pockets therein, means for laterally swinging the brackets and the articles therein from a horizontal, receiving position to an inclined, coating position to project portions of the articles into said spray as the articles pass said spray coating means, means for positively rotating the articles about their axes when in the latter position, and fixed guide means for retaining the articles in said pockets during the rotation thereof.

6. A machine for spray coating the exterior surfaces of outwardly projecting seaming flanges of containers or the like, comprising a plurality of container receiving brackets mounted for movement along a predetermined path and adapted to receive containers in horizontal position, spray coating means adjacent said path, means for laterally swinging the brackets from said horizontal position to an inclined position to project said flanges into the spray area as they pass said spray coating means, means for rotating the containers while in the latter position, and guide means for preventing the containers from dropping out of said brackets when in the latter position, said guide means comprising a fixed rail disposed opposite the lower end of the containers and another rail opposite the side wall thereof.

7. A machine for spray coating the exterior surfaces of outwardly projecting seaming flanges of can bodies or the like, comprising a plurality of brackets having pockets adapted to receive the bodies in horizontal position, means for moving the brackets along a predetermined path, a downwardly projecting spray gun adjacent said path, means for swinging the brackets and the bodies therein laterally with respect to said path from said horizontal position to an inclined position where said seaming flanges are disposed below and in alignment with said spray gun, and means for rotating the bodies while in the latter position, said means comprising an endless belt having a flight positioned to be engaged by the side walls of the bodies when moved to the last-mentioned position, and means for driving said belt.

8. A machine for coating the exterior surfaces of outwardly projecting seaming flanges of can bodies or the like, comprising a plurality of brackets having pockets adapted to receive the bodies in horizontal position, means for moving the brackets along a predetermined path, a downwardly projecting spray gun positioned laterally adjacent said path, means for swinging the brackets and the bodies therein from said horizontal position to an inclined position laterally to project said seaming flanges below said spray gun, and means for rotating the bodies in said pockets when in the latter position, said means comprising a belt trained for movement in a plane perpendicular to the axes of the bodies when in said inclined position and having one flight thereof in position to be engaged by the side walls of the cans as they are moved to said inclined position, and means for moving said belt.

9. A machine for coating the exterior surfaces of outwardly projecting seaming flanges of can bodies comprising a plurality of brackets having pockets adapted to receive the can bodies in horizontal position, means for moving the brackets along a predetermined path, an endless belt

trained for movement on an inclined plane with its lower flight disposed adjacent the path of movement of the brackets, means for driving said belt, a downwardly projecting spray gun adjacent said belt, and means for swinging the brackets and the can bodies therein from said horizontal position to an inclined position wherein the side walls of the bodies engage said belt as the brackets move past the spray gun, whereby the seaming flanges of the bodies are moved beneath said gun and the bodies are rotated.

10. A machine for coating the exterior surfaces of the seaming flanges of can bodies, comprising a conveyor chain trained for movement in a vertical plane, horizontally disposed can-holding brackets pivotally mounted on the chain for transverse pivoting movement relative to the chain, a pair of sheaves spaced longitudinally of and disposed above the upper flight of the conveyor, a belt trained about said sheaves, means for driving said belt, a spray gun opposite said belt and between the sheaves, and means for swinging said brackets upwardly as they move between said sheaves, to cause the can bodies to engage said belt, thereby to rotate the bodies as they pass beneath said gun.

11. A coating machine comprising a coating chamber, a pair of sheaves disposed exteriorly of the chamber at opposite ends thereof, a belt trained about said sheaves and having one flight thereof extending through the chamber, a chain trained for movement through the chamber, article-holding brackets on the chain, means for raising the brackets as they move through the chamber to urge the articles supported thereby into contact with said belt, to cause the articles to be rotated and spray gun coating means in the chamber positioned to direct a spray of coating material upon the articles when in the raised position and while being rotated by the belt.

12. A coating machine comprising a housing

defining a coating chamber, a spray gun carried by the chamber and projecting downwardly thereinto through the top wall thereof, a downwardly extending flue below the gun, means spaced to one side of the gun and out of the path of the spray projected thereby for conveying articles to be coated through said housing, means for tilting the articles as they pass therethrough to project the ends thereof into the path of the spray projected by the gun, and means for rotating the articles while in the last-mentioned position.

13. A coating machine comprising a housing defining a chamber having a coating section and a laterally spaced conveyor section adjacent thereto, a spray gun in the coating section, a conveyor extending through the conveyor section, a plurality of brackets pivotally mounted on said conveyor and adapted to support, in the conveyor section, the articles to be coated, and means for swinging the brackets and the articles supported thereby upwardly and laterally, to project at least a portion of the articles from the conveyor section into the coating section into operative relation to said gun.

14. A coating machine comprising a housing defining a chamber having a coating section and a laterally spaced conveyor section adjacent thereto, a spray gun in the coating section, a conveyor extending through the conveyor section, a plurality of brackets pivotally mounted on said conveyor and adapted to support the articles to be coated, means for swinging the brackets and the articles supported thereby upwardly and laterally, to project at least a portion of the articles into the coating section into operative relation to said gun, and means for rotating the articles when in the last-mentioned position.
